SHOCK-RESISTANT FLUORESCENT LAMP
HOLDER

Emanuel Fuchs, Jersey City, N. J.

Application November 14, 1942, Serial No. 465,620

6 Claims. (Cl. 240—78)

This invention relates to holders for fluorescent lamps and particularly to the means for holding the various parts of the lamp operating device properly in place in the holder.

Considerable difficulty has previously been experienced in securing the various electrical devices which are customarily interpolated in the circuit to a fluorescent lamp, in place in the holder therefor adequately to resist physical shocks such as those which are caused by concussions, impact or vibrations. The parts become displaced under such shocks and fail to function and sometimes even fall out of the holder or housing for the lamp. Ordinary fastening means have not proven effective, particularly when the lamps are used on war vessels and the like where heavy shocks and concussions are to be expected.

The invention therefore contemplates the provision of an efficient lamp holder or fixture highly resistant to shock and adapted to function even under severe stresses and wherein readily detachable means are provided to secure the parts firmly and adequately in their proper operative positions and in such a manner that the parts are easily accessible and removable for replacement and repair, said means however, so suspending the parts held thereby that breakage or displacement under the severe stresses is minimized.

The invention further contemplates the provision of a simple, economical and efficient but quickly detachable lock for the lamp or plurality of lamps in the holder to prevent their displacement or detachment when the fixture is subjected to heavy shocks or vibrations.

The various objects of the invention will be clear from the description which follows and from the drawings, in which,

Fig. 1 is a combined fragmentary front view and vertical section of my improved holder.

Fig. 2 is a vertical section of the same taken on the line 2—2 of Fig. 1.

Fig. 3 is a fragmentary front view and partial section of the lamps as they appear inserted into the sockets therefor and removably locked in place by the lamp lock.

Fig. 4 is an end view of the same.

Fig. 5 is a similar end view of a modified form of the lamp lock as applied to a single lamp.

Fig. 6 is a similar end view of the lamp lock with its clamping bolt omitted.

Fig. 7 is a fragmentary bottom plan view of part of the lamp housing showing the means for securing the lamp ballast or transformer in position.

Fig. 8 is a fragmentary vertical section of the same.

Fig. 9 is a fragmentary bottom plan view of the starter switch and button showing the securing means therefor and the spring for maintaining the starter button in position.

Fig. 10 is a fragmentary front view and partial vertical section of the same.

In the practical embodiment of the invention shown by way of example, the lamp housing 11 is preferably, though not necessarily, formed of plastic sheets, plates or molded parts comprising the one-piece top front and back member 12, the end members 13 and the shade member 14. Suitable angle corner braces 15, 16 preferably of suitably bent sheet metal, and the U-shaped shade strap 17 serve as the means for bracing and securing the housing parts and also serve as a support means for the attachment thereto of other parts as will be more fully described hereinafter.

To support the lamp sockets as 18, 19, said sockets are secured to the member 20 which is in the shape of an inverted U extending substantially the entire length of the housing and having a pair of depending legs. Each of said legs is fastened to an angle brace 16 as by means of a screw 21 engaging the nut 22 (Fig. 7) secured to the upright leg of said brace. As best shown in Figs. 1 and 10, the member 20 is in inward spaced relation to the housing 11. To receive the prongs 23, 24 of the lamp 25, the socket 18 is provided with a pair of parallel slots 26, 27 extending inwardly from the edge thereof and open at said edge, there being suitable electrical connections (not shown) in the slots to supply current to the lamp. Where a multiplicity of lamps is held in the fixture, each socket for the lamps is similarly slotted.

I have found, however, that the prongs of the lamps 25 and 28 cannot be properly retained in the socket slots provided therefor, in those cases where the lamp assembly is subjected to shock, heavy vibrations or comparatively severe concussions. I have therefore provided a lock for removably securing any number of lamps such as the twin lamps 25, 28 or a single lamp in the corresponding sockets. As best shown in Figs. 3, 4 and 6 wherein the invention is shown applied to twin lamps, a circumferential groove as 29 is made in the end portion of the lamp in slight inward spaced relation to its end surface. Into the groove is inserted the flange 30 of each of the similar but opposed locking members 31, 32. Each of said members is preferably made of

sheet metal and is provided with a pair of spaced partly cylindrical walls 33, 34 each less than a half cylinder in extent and joined by the wall 35 having a hole 36 therein for the passage of the bolt 37. Said wall 35 is arranged intermediate the axes of the cylindrical walls and the outermost portions of said walls. In the operative position of the lock, the cylindrical walls 33, 34 engage the corresponding cylindrical walls of the sockets 18, 19, while the connecting wall 35 is arranged between the sockets. When the wing nut of the bolt 37 is tightened with the members 31 and 32 in place around the sockets, the flanges 30 are more deeply inserted into and locked in the lamp grooves 29, thereby preventing the lamp prongs from moving out of the socket slots, the open ends of said slots being closed off. Nor can the lock members move relatively to the sockets in any direction by reason of the flange 30 and the clamping action of the bolt which forces the walls 33, 34 of each of the lock members toward the corresponding walls of the other lock member thereby to clasp and clamp the sockets between them.

To provide for adjustment, the respective ends 38, 39 of the lock members are spaced apart a proper comparatively small distance in the normal locking positions thereof. The flange 30 is also preferably cut away at the walls 35 to make said walls somewhat flexible and thereby to aid in the locking action by permitting sufficient tightening of the bolt and the consequent exertion of the required pressure upon the socket clamping parts 33, 34.

In the form shown in Fig. 5, the lock member 40 may be made of one piece having the cylindrical wall 41, the end walls 42, 43 and the outstanding spaced flanges 44, 45, the flanges being preferably omitted at the top to give flexibility to the lock member, said flanges being also omitted at the walls 42, 43 for the same reason. The flanges 44, 45 lock into the groove 29 in the lamp as heretofore explained in connection with the description of the lock members 31, 32. It will be understood that there are as many walls 33 or 34 as there are sockets and lamps to be held, and that the wall 35 is provided between each set of walls 33, 34, so that the lock is applicable to any number of lamps to be mounted in the fixture.

To hold the lamp ballast 46 in place, the flanges 47 projecting from the ends of the ballast are bolted as by the bolts 48 to the member 20 with a suitable heat-resistant washer as 60 therebetween. While this construction is sufficiently strong for ordinary use of the lamp assembly as in buildings, it has been found inadequate in places where concussions and shocks are frequent, as on board war vessels. I have therefore provided simple means, resistant to heavy shocks, but slightly yieldable thereto, for holding the ballast. As best shown in Figs. 7 and 8, the longitudinally arranged strip 49 is interposed between the ballast and the member 20, and the parallel reinforcing strip 50 is arranged against the under side of the top of the housing member 12, the heat resistant and insulating washers as 51 being interposed between the strips 49 and 50 to form a suspension slightly yieldable under shocks, for the strip 49 and the ballast. The strap 52 is shaped to pass underneath the ballast and is provided with end flat securing ears 53. Said ears, together with the strips 49 and 50 and the washers 51 are all held firmly but slightly yieldingly to the housing and against the member 20 by the

bolts 54, the strip 49 serving also to brace the member 20 and to limit the extent to which it yields under heavy stresses. A number of such straps 52 are provided at longitudinally spaced intervals along the ballast, the straps eliminating the danger of displacement of the lamp ballast under the unusual stresses mentioned while providing a limited amount of flexibility.

Another point where weakness may develop and displacement of the parts may occur under high pressures such as are produced by shocks or concussions is at the starter switch button 55 (Figs. 9 and 10). The flat spring 56 is therefore provided to urge the button toward its normal position and to maintain it in that position under the unusual stresses mentioned while serving to absorb some of the shock by its yieldability. Said spring has a flat portion 57 engaging the end surface of the button and terminating in a free end, while at its other end the spring is secured to the bracket 58 as by the bolt 59. The bracket is in turn fastened by any suitable means (such as spot welding) to the angle corner member 15. The starter switch 61 is suspended from the member 20 as by means of the Z-shaped bracket 62 having one arm secured to the switch and the other arm secured to the member. The reflector 63 may be suitably perforated or cut away for the passage therethrough of the starter button. While the spring 56 permits the button to yield a certain amount under heavy stresses, it is stiff enough to do its work of maintaining the button in its proper position at all times.

It will be seen from the above, that I have provided a mounting for the parts of fluorescent lamp fixture, which while capable of absorbing some of the heavy shocks to which such fixtures may be subjected in certain installations, adequately maintains the parts in their proper positions and permits them to function properly nevertheless under such shocks, and that I have provided a device well designed to withstand and meet the severe conditions of practical use.

While I have shown and described certain specific embodiments of my invention, it will be understood that certain changes may be made therein without departing from the spirit of the invention or the scope of the appended claims.

I claim:

1. In a shock-resistant fixture for fluorescent lamps, a housing, a support member within the housing, and in the shape of an inverted U, a lamp socket secured to the support and having a pair of parallel prong-receiving slots therein, a tubular lamp having terminal prongs thereon adapted to enter the slots and having a circumferential groove therein adjacent the inner ends of the prongs, means for removably locking the lamp in the socket comprising a member arranged to clasp the socket and having a flange thereon entering the groove of the lamp and a bolt to clamp the member to the socket and to lock the flange in said groove, a lamp ballast in the housing, a plurality of straps passing around the ballast and secured to the housing, a starter switch button secured to the housing, and a spring urging the button toward its operative position and maintaining it in said position.

2. In a shock-resistant fixture for a fluorescent lamp, a housing, a lamp socket in the housing, a lamp ballast in the housing, a starter switch having a starter button within the housing, a support in the housing in the shape of an inverted U for supporting the socket, means for securing the ends of the ballast to the support, a strap pass-

ing around the inner surface part of the ballast and having end portions secured to the housing, a transverse strip interposed between the support and the strap and between said end portions and the housing, a spring secured to the housing and having a free end portion engaging the starter button, and a lock for the lamp having a portion thereof clasping the socket and having a flange thereon entering a groove in the lamp.

3. In a shock-resistant fluorescent lamp fixture having a lamp socket, a lamp ballast and a starter switch button, a housing, a support in the housing in the shape of an inverted U for the socket, the ballast and the button, a shock-resistant lock for the lamp including a flanged locking member and means to secure the member to the socket, a series of spaced transverse straps for the ballast secured to the housing, and a spring engaging the button and secured to the housing.

4. The combination with a pair of fluorescent lamps each having a circumferential groove therein, of a socket for each lamp, a pair of similar locking members each having a pair of longitudinally spaced socket clasping portions and a substantially flat wall joining said portions, said wall being arranged inwardly of the outermost part of the clasping portion and outwardly of the

center line joining the centers of the sockets, a flange outstanding substantially perpendicularly from the peripheral edge of each of the portions and entering the groove, and a bolt passing through the walls and positively locking said members together against relative movement and against movement in the socket.

5. In a shock-resistant fluorescent lamp fixture having a starter switch provided with a starter button, a housing, a support member in the housing in the form of an inverted U, means suspending the switch from the support member, a spring having a free end portion engaging the button and urging said button toward the switch, and means securing the other end portion of the spring to the housing.

6. In a shock-resistant fluorescent lamp fixture having a lamp ballast, a reflector and a housing, a support member within the housing and in the shape of an inverted U, and a series of spaced transversely arranged strap members each having a pair of spaced aligned flanges secured to the support member and each having a depending part between the flanges passing around the inner side of the ballast, said ballast and strap members being arranged between the reflector and the support member.

EMANUEL FUCHS.
